UNITED STATES PATENT OFFICE.

FRANK PRIMOSHIC, OF WOODSIDE, NEW YORK, ASSIGNOR TO RALPH H. BINNS AND EDWARD H. BINNS, BOTH OF PITTSBURGH, PENNSYLVANIA.

BUTTON.

Application filed May 12, 1922. Serial No. 560,321.

To all whom it may concern:

Be it known that I, FRANK PRIMOSHIC, a citizen of the United States, and resident of Woodside, in the borough of Queens, county 5 of Queens, and State of New York, have invented a new and Improved Button, of which the following is a full, clear, and exact description.

My invention relates to a button, and aims 10 to provide a device of this nature which may be associated with a closure for actuating the same.

It is a well appreciated fact that closures have been placed upon the market which closures embody a pair of strips each presenting members adapted to interengage with each other to lock the closure together with an actuating member which co-operates with the strips to effect this engagement as well 20 as dis-engagement of the members with each other. Also a pull element has been associated with the actuating member by means of which the same was moved with respect to the closure strips.

25 Certain objections have been noted in connection with this latter element, in that the same presents a rather unsightly appearance which is not desirable when the closure is placed in certain applications. A further 30 objection has been noted incident to the fact that when the closure strips were interlocked, the same have been visible, which is extremely objectionable, and as the closure was utilized this visibility has increased in 35 cident to the fact that the actuating member has naturally spread the coverings overlying the closure strip, apart, incident to this engagement of the same.

Thus it is an object of the present invention 40 to provide a cover member in the nature of a button which may be utilized in numerous applications but which is primarily intended for use in connection with a closure of the nature stated, and is adapted to act as 45 a substitute for the pull element commonly associated with the actuating member of the closure.

It is a further object of the present invention to provide a device of the nature 50 stated which will co-operate with these portions of the covering to which the closure strips are affixed, in such a manner so as to force the same into proper position thus covering the closure and overcoming any objec-

tion incident to unsightly appearance, it being further noted that by means of my improved device, the material with which the closure strips are associated may have its edges almost completely abutting, contrary to conventional construction in which its 60 edges are necessarily spaced from each other.

Still another object of this invention resides in the provision of a button capable of being constructed at a relatively nominal figure, and which will permit of the actuating member being operated more readily.

With these and further objects in mind, the present invention has reference to a body adapted to be associated with the actuating member of a closure so that the actuating 70 member is moved to operate the closure, this body further co-operating with the covering with which the closure is associated, to produce the result aforementioned.

It will be seen in the attached sheet of 75 drawings that a practical embodiment has been illustrated and in these views it will be noted that—

Figure 1 is a face view of a button embodying my improved construction and 80 showing the same associated with the actuating member of a closure of the nature specified, the latter being affixed to a covering.

Figure 2 is a sectional side view taken along the line 2—2 and in the direction of 85 the arrows indicated in Figure 1.

Figure 3 is a face view of the button and showing the same in partly open position.

Figure 4 is a view similar to Figure 3 but showing the parts of the button in completely open position.

Figure 5 is a side elevation of the device as illustrated in Figure 4, and

Figure 6 is a sectional plan view taken along the line 6—6 and in the direction of 95 the arrows indicated in Figure 1.

It will be seen in these various views that the reference numerals 10 and 11 indicate the two portions of the material with which the closure is to be associated, the said closure, in the embodiment illustrated including a pair of strips 12 providing in the usual manner outwardly extending headed arms 13, the arms of one strip being adapted to extend into the space existing between the arms of the second strip, and to have their heads engaging recesses in the under side of the latter arms.

However, in accordance with customary construction, an actuating member 14 co-operates with these strips and serves to cause an inter-engagement and dis-engagement of the same in the well known manner, it being further noted that my improved type of button is shown as being in association with this actuating member, and in lieu of the pull element commonly affixed to the same.

10 Referring to the construction of the button, it will be seen, attention being particularly invited to Figures 4 and 5, that the same includes a backing plate 15, which, in the embodiment illustrated, forms a part of the actuating member 14, and affixed one to each end of the backing plate by means of hinges 16, are cups 17 and 18, the latter being sufficiently small to fit within the former when both of the same are swung to a closed position, such as has been shown in Figure 2.

Further it will be noted that the tongue 19 is associated with the cup 18 and is adapted to extend through an opening 20 forming a part of the cup 17 when both of these cups are in closed position. In this connection it will be also noted that the cup 17 carries a catch member 21, which, when the cups are in closed position is adapted to co-operate with the cup 18 at a point adjacent the point of hinged connection 16 of the latter. Thus in closed position, the cup 18 primarily swings to the position shown in Figure 2, subsequent to which the cup 17 is swung to a point at which it will overlie the cup 18. During this latter operation, the tongue 19 will enter the opening 20, and thus, incident to the engagement of this tongue with the edge of the opening, any movement of the cup 18 with respect to the cup 17 will be prevented, and it will be necessary, in order to move the cup 18 to the position shown in Figure 5, for an operator to disengage the catch 21 of the cup 17 and to swing the latter in order to effect this operation.

Thus it will be seen that the objects of this invention have been accomplished incident to the fact that an object of extremely pleasing appearance and simple construction is presented, and by associating this element with the actuating member 14, the latter may be pulled upwardly by the cup 17, or downwardly by the cup 18, to open or secure the closure parts. Further, due to the fact that the bodies of both the cups 17 and 18, as in Figure 6, are spaced from the backing plate 15 with which they are associated, it will be noted that a groove is presented within which the edges of the material portions 10 and 11 ride, the latter being thus retained in proper position, and assuming when the closure is engaged, a

position at which their edges will nearly abut, as in the lower portion of Figure 1.

It will be understood that numerous modifications of structure might readily be resorted to without in the least departing from the scope of my claims; which are;

1. In a separable fastener, interlocking elements, an actuating member for interlocking and disengaging said elements, and a cover for said member pivotally connected thereto.

2. In a separable fastener, separable elements operating to successively lock and unlock, means for locking and unlocking said elements, and a cover for said means pivoted thereto.

3. In a separable fastener, separable elements operating to successively lock and unlock, means for locking and unlocking said elements, and a cover for said means including cooperating members, each of which is connected to one end of said means and providing a grip for operating said means.

4. In a separable fastener, separable elements operating to successively lock and unlock, means for locking and unlocking said elements, and a cover for said means including cooperating members pivoted to said means and nested one within the other when the same are in covering position.

5. In a separable fastener, separable elements operating to successively lock and unlock, means for locking and unlocking said elements, and a cover for said means including cooperating members pivoted to said means and nested one within the other when the same are in covering position, said cooperating members providing grips for operating said actuating means.

6. In a separable fastener, separable elements operating to successively lock and unlock, means for locking and unlocking said elements, a cover for said means including cooperating members pivoted to said means and nested one within the other when the same are in covering position, and means for retaining said cooperating means in covering position.

7. In a separable fastener, separable members operating successively to lock and unlock, an actuating member for locking and unlocking said separable members, a backing plate for said actuating member, and a cover for said actuating member including cooperating members pivoted to said actuating member, one of said cooperating members engaging said backing plate and the other engaging the first named cooperating member when said members are in covering position.

FRANK PRIMOSHIC.
